CLAIM

The ornamental design for a desktop container, as
shown and described.

DESCRIPTION

FIG. 1 is a front elevational view of a desktop container showing my new design;
FIG. 2 is a rear elevational view thereof;
FIG. 3 is a bottom plan view thereof;
FIG. 4 is a top plan view thereof; and,
FIG. 5 is a right side elevational view thereof; the left
side elevational view appears the same as the right side
elevational view.

FIG. 1

FIG. 2

FIG. 3

FIG. 4

FIG. 5
